UNITED STATES PATENT OFFICE

2,413,556

METHOD OF PACKAGING CELLULOSIC PADS

Charles A. Fourness, Appleton, and Kenneth J. Harwood, Neenah, Wis., assignors to International Cellucotton Products Company, a corporation of Delaware

Application December 3, 1942, Serial No. 467,752

5 Claims. (Cl. 226—2)

1

The present invention relates to compressed, multi-ply, creped cellulosic products and to improved methods and procedures for packaging such products. Products of this general type comprise a pad or bat which is made by superposing a plurality of generally flat sheets or layers of thin, creped, cellulosic tissue and then compressing the bat lengthwise in a direction substantially perpendicular to creping therein so as to reduce the length of the pad or bat, without substantial change in the thickness or width thereof, and to increase the unit density of the pad or bat within the range of about 2 to 20 times. The individual sheets may be of plain cellulosic tissue or they may contain asphalt or other materials.

As will hereinafter appear, the present invention is concerned particularly with pads or bats made of plain tissue, this product being widely used in hospitals for surgical and related purposes. For this use, the compressed product has very great advantages: it can be readily handled, stored, and transported while in the compressed state, and it can be re-expanded to the normal, low density, high absorptive state by simply stretching the pad or bat. These characteristics of the product are of great value in normal times, and are of particular value in time of war.

However, certain difficulties have arisen in the provision of satisfactory packaging for the compressed material. Since the material is used mainly for surgical purposes the package must be air tight and capable of being made sterile. To save weight, shipping and storage space the package should be light and should occupy a minimum of space. At the same time the package must be quite strong mechanically, in order to hold the pad or bat in the compressed state, and to facilitate handling and storage the package must remain flat until opened for use. The packaging procedures heretofore known to the art have not provided a package capable of meeting the above requirements, and the principal object of the present invention is to provide an improved packaging procedure which shall fully satisfy all of the above stated requirements.

As will hereinafter appear this object is accomplished by the provision of a novel, improved package of compressed cellulosic material of the above described general type, and method for making the same. The novel features and advantages of the invention will be made more apparent by reference to the accompanying draw-

2

ings and the following description of certain preferred embodiments thereof. In the drawings:

Fig. 1 is a plan view of an apparatus which we have found particularly suitable in the practice of the present invention;

Fig. 2 is a sectional view on the general line 2—2 of Fig. 1;

Figs. 3, 4, 5, and 6 are enlarged, fragmentary, sectional views on the lines 3—3, 4—4, 5—5 and 10 6—6, respectively, of Fig. 1;

Fig. 7 is a perspective view of a compressed pad or bat of the type to which the present invention relates before packaging;

Fig. 8 is a perspective view illustrating an intermediate step in one of the packaging procedures of the present invention;

Fig. 9 is a perspective view, partially in cut away section, showing the completed package with the compressed pad or bat in place therein; 20 and

Figs. 10 and 11 are perspective views partially in cut away section of a modified or alternate packaging arrangement.

A pad or bat product of the general type to 25 which the present invention relates is illustrated at 11 in Fig. 7. The pad or bat 11 comprises a plurality of superposed sheets 13, as illustrated in the enlarged portion of Fig. 7; the creping in all or substantially all of the sheets extends in the 30 same direction, and the individual sheets 13 have a basis weight (i. e., weight of flat uncreped sheets) within the range of from 4 to 9 pounds for 480 sheets, 24 x 36 inches. In the products used for hospital or surgical purposes, the sheets 35 13 normally contain in excess of 95% of pure cellulosic fiber. The sheets 13 are manufactured on the Yankee type machine and as manufactured they have a crepe ratio (i. e., the ratio of the length of the uncreped sheet to the length of the 40 creped sheet) of from about 2 to 3.

In making the compressed pad 11, a proper number of the sheets 13 are superposed one on top of the other with the creping in all or substantially all of the sheets running transversely to 45 the length of the bat. The pad or bat is then longitudinally compressed, preferably without substantial change in its thickness or width, to reduce its length and simultaneously to increase the unit density thereof within the range of from 50 2 to 20 times. Apparatus such as that disclosed in Neller Patent No. 2,303,087, which is assigned to the assignee of this invention, may be used for effecting this compression.

As previously pointed out, the product used for 55 hospital or surgical purposes must be packaged

in such manner that a completely air tight, sterile package will be provided, and the package must be capable of holding the pad or bat flat and in the desired compressed state. The obtaining of a package capable of satisfying these requirements is complicated, because of the tendency of the compressed product to re-expand following the compressing operation. This necessitates the use of a strong restraining means for holding the pad or bat in the package, while at the same time, to save space, it is necessary that the package shall not add materially to the bulk of the product.

The apparatus which we prefer to use in the manufacture of the package and product of our invention is illustrated as a whole in Fig. 1, and detailed illustrations are contained in Figs. 2 and 6. Generally, the apparatus comprises a belt type compressing mechanism which effects controlled recompression of the pad or bat preliminary to the packaging, means for holding the pad or bat in the compressed state when it is discharged from the compressing mechanism and while an initial wrapping or container is applied thereto, and a second holding means which holds the compressed pad or bat in its initial wrapping while a second wrapping or container is put in place thereon.

In the practice of the present invention, pads or bats 11 which have previously been compressed, and which have been cut to proper size, are delivered to a work table indicated generally at 17, in Fig. 1. Because of the stresses set up within the compressed product during the compressing operation, there is substantial re-expansion of the cut pads or bats 11 before they reach the work table 17. As a result recompression is necessary, in order to restore the compressed pad or bat to the desired density and dimensions for packaging.

The re-compressor includes a converging nozzle or chute 19 which is rectangular in cross section and through which the pad or bat 11 is propelled by means of two flexible belts 21, which of themselves form two of the sides of the nozzle. The top and bottom of the nozzle or chute 19 may comprise flat, polished, metal plates 23 and 25, and to facilitate entry of the pad or bat therebetween, the upper plate 23 may be cut away and beveled as illustrated at 27.

The belts 21 may be of any suitable composition material, and should have a width substantially equal to the separation of the top and bottom plates 23 and 25. The belts are supported upon suitable pulleys 29 and are driven at equal linear speed by any suitable means, not shown. It is desirable that backing supports be provided for the belts 21 as illustrated at 31; considerable stress is required to compress the pads or bats 11 as they pass through the chute 19, and in the absence of these backing supports 31 excessive belt tension may be required.

The re-compressor chute 19 discharges into a bat holding structure which comprises a pair of opposed, flat surfaced, jaw members 33 and 35 made of sheet metal and provided with V-shaped slots 37 for facilitating the grasping and handling of the pad or bat after the initial wrapper or container is applied thereto. The details of the jaw members 33 and 35 are shown particularly in Figs. 2 and 3. The lower jaw 35 is fixedly supported, at its inner end only, upon the table 17 with its upper surface co-planar with the upper surface of the bottom plate 25 of the chute 19. The outer edges of the lower jaw are

turned up as illustrated at 39 in Fig. 3, the spacing of the turned up portion 39 being approximately equal to the desired final width of the pad or bat. The upper jaw 33 is of a complementary shape having downwardly depending side portions 41 which extend over the upstanding side portions 39 of the lower jaw 35 as illustrated particularly in Fig. 3. The upper jaw 33 is hingedly supported for rotatable movement toward and away from the lower jaw 35 by means of a shaft 43, which is supported on the work table 17 by suitable bearing supports 45, and is biased in the direction of the lower jaw 35 by adjustable tension springs 47. Both jaws are thus provided with a cantilever type support which, as will hereinafter appear, is of importance in making possible the convenient practice of the procedure of the present invention.

The mechanism for applying the second or outer wrapper or container to the pad or bat 11 includes a flat support plate 49 which is supported on the work table 17 by a guide member 51 and frame members 52. The upper surface of the plate 49 is co-planar with the upper surface of the lower unit 55 of a second pair of jaw members 53 and 55. The Jaw members 53 and 55 are likewise formed of sheet metal and are provided with cut-away, generally V-shaped, slots 57 for facilitating the handling and grasping of the pad or bat during the packaging operation. The lower jaw member 55 is fixedly supported, at its inner end only, on the work table 17 and has upstanding side portions 59. The upper jaw member 53 has depending side portions 61 which extend along and cooperate with the corresponding side portions 59 of the lower jaw member 55. The upper jaw member 53 is hingedly supported on the work table 17 so as to be movable toward and away from the lower jaw member 55 by a shaft 63 and suitable bearings 65. If desired, adjustable tension springs 67, similar to the springs 47, may be provided for biasing the upper jaw 53 in the direction of the lower jaw 55.

As previously stated, the compressed pads or bats 11 are received at the work table 17 in a somewhat expanded state. As the first step in the packaging procedure of the present invention, one of these pads 11 is placed on the left hand table portion 68 of the lower plate 25, and is pushed into the space between the upper and lower plates 23 and 25 of the recompressor chute 19. The belts 21 which move in the directions indicated by the arrows in Fig. 1, carry the pad or bat 11 through the recompressor chute 19 and propel it into the space between the two jaws 33 and 35. This movement of the pad 11 through the converging chute 19 effects automatic recompression of the pad, and since the recompressed pad is immediately moved into the space between the jaw members 33 and 35 re-expansion thereof is prevented by the jaw members.

Prior to the recompressing operation, a tube or sleeve 69 of paper, fabric, or other sheet material is slipped over the jaws 33 and 35 as illustrated in Figs. 1, 2, and 3. This sleeve should have a length approximately equal to the length of the pad 11 and a perimetrical dimension which is likewise approximately equal to the corresponding dimension of the pad 11. The inside dimensions of the jaws are likewise approximately equal to the dimensions desired in the final product. The movability of the upper jaw 33 is relative to the lower jaw 35, and the cantilever support means for the jaws permits the sleeve 69 to be readily slipped thereover.

The operation of the recompressor forces the recompressed pad or bat 11 between the two jaw members about which is disposed the sleeve 69, as above stated. With the pad 11 in this position, it is possible for the operator to grasp both the pad 11 and the sleeve member 69 in the areas exposed by the slots 37 in the jaw members and to withdraw both the sleeve and the pad simultaneously from the jaws. If necessary, the jaws may be slightly compressed in order to facilitate this movement.

The sleeve 69 will now be positioned about the pad 11 with its longitudinal axis extending substantially parallel to the lines of creping in the constituent sheets making up the pad 11, as illustrated in Fig. 8. The tubular sleeve 69 which is joined along the edges 71, has sufficient strength to restrain the pad or bat from longitudinal expansion, but this arrangement will not prevent buckling in all instances, and it does not provide an air and dust-tight package which is desired.

As the next step in the packaging procedure of the invention, the pad or bat 11, with the sleeve 69 in place thereon, is placed upon the platform plate 49 against the guide 51 and is slid in the direction of its width into position between the jaws 53 and 55, as illustrated particularly in Figs. 1, 5, and 6. It will be noted that the lines of creping in the pad 11 and the closed sides of the sleeve 69 extend crosswise of the second pair of jaws, a change of position of 90° as compared with the position of the pad in the first pair of jaws, while the pad or bat 11 and the restraining sleeve 69 are held in position between the second pair of jaws 53 and 55. The second or outer wrapping, which preferably comprises a bag member 73 of heavy kraft paper, or other suitable sheet material, open only at one end, is slid over the jaws as illustrated in Figs. 1 and 6. The longitudinal axis of the bag 73 thus extends at right angles to the longitudinal axis of the sleeve 69 and to the lines of creping in the constituent. When the bottom of this bag 73 reaches the end of the pad or bat 11 and its confining sleeve 69, the entire combination may be removed as a unit by simply pulling it away from the jaws 53 and 55, the cut-away V-shaped slots 57 which are provided in the jaws and the cantilever type support for the jaws facilitating this operation. The end 75 of the outer bag covering 73 may then be folded over and sealed in the usual manner as illustrated in Fig. 9.

The above described procedure constitutes a most satisfactory means of packaging products of the described type. Apparently because of the provision of the inner restraining sleeve 69 and the outer bag covering 73, and the location of those elements with the maximum strength portions thereof extending at right angles to each other, the normal tendency of the compressed pad or bat 11 to expand and to buckle is completely prevented. At the same time, when it is desired to use the product, the inner sleeve 69 can be easily severed so as to permit convenient withdrawal of any desired amount of the compressed product from the outer bag covering without having to remove the entire compressed pad or bat from the package. This, of course, is very advantageous in maintaining the high standards of cleanliness which are essential in surgical work.

The packaging procedure as described is rapid. It requires a minimum of machinery, and hence,

in addition to providing a highly efficient and very satisfactory package, it may be practiced at very low cost.

As an alternative to the packaging procedure described above, the inner wrapping or container may comprise a bag of paper, fabric, or other suitable sheet material, and for certain purposes this packaging arrangement possesses particular advantages. A package which includes this type of inner wrapping is shown in Figs. 10 and 11, and it will be noted that the bag member 77 is of substantially the same shape and dimensions as the compressed, multi-ply pad or bat 11 which is contained therein. The sides of the bag 77 are closed, so as to form a retaining sleeve which is generally similar to the retaining sleeve 69, by overlapping edges 79 adhesively attached together, and one of the ends of the bag is closed by a folded-over flap 81 which is glued or otherwise attached in place as illustrated. The other end of the bag is left open, as illustrated in Fig. 11, and it is desirable that the depth of the bag should be equal to or slightly less than the width of the pad or bat 11 when measured in a direction lengthwise of the creping in the constituent sheets.

The bag 77 is applied to the pad or bat 11 in substantially the same manner as the sleeve 69 in the previously described procedure, that is, the bag 77 is slipped over the cantilevered jaws 33 and 35 located at the discharge end of the recompressor unit, prior to the recompressing operation and the recompressed pad or bat 11 is discharged directly into the bag 77 at the conclusion of the recompressing operation. The longitudinal axis of the bag 77 extends parallel to the lines of creping in the sheets which make up the pad 11. The bag 77 with the pad or bat 11 in place therein may then be removed from the jaws 33 and 35 by grasping both the pad and the bag in the area of the cut-out slots 37 and pulling both units out of the open end of the jaws.

Following this operation, an outer bag covering 83 which may be generally similar to the bag covering 73 is applied to the combination of the pad 11 and the bag 77 in substantially the same manner as in the previously described embodiment. The resultant package effectively retains the pad or bat 11 in the compressed state without buckling. At the same time it is air-tight, and the contents can be rendered surgically sterile by conventional sterilization procedures. Also of importance the actual packaging means occupy very little bulk and do not materially increase the weight of the product. Similarly to the previously described package, the retention of the compressed pad or bat 11 against expansion and without tendency to buckling appears to result from the provision of the dual restraining sleeves provided by the inner open ended bag 79 and the outer sealed bag 83, which are so positioned that the longitudinal axes thereof extend at right angles to each other.

Various other packaging procedures embodying the principles disclosed in the foregoing may be suggested to those skilled in the art. Accordingly, it is desired that the accompanying claims should be accorded the broadest reasonable construction consistent with the language appearing therein and the prior art.

We claim:

1. The method of packaging a multi-ply, previously compressed and expanded, creped, cellulosic pad of the class described, which comprises

the steps of recompressing the pad in a lengthwise direction while maintaining the width and thickness of the pad substantially uniform, restraining the recompressed pad against longitudinal expansion or buckling while a sleeve member having longitudinal and peripheral dimensions substantially equal to the equivalent dimensions of the recompressed pad is placed about said recompressed pad, and then applying a close fitting, outer covering including a sleeve portion to the combination of said pad and sleeve so that said outer covering extends at right angles to said first mentioned sleeve.

2. The method of packaging a multi-ply, previously compressed and expanded, creped, cellulosic pad of the class described which comprises the steps of recompressing the pad to the dimensions desired in the final package, applying a confining sleeve to said recompressed pad while said pad is held against expansion or buckling, said confining sleeve having substantially the same longitudinal and peripheral dimensions as said recompressed pad and being applied thereto in such manner that it resists re-expansion of said pad or bat, and then applying an outer wrapping which includes a sleeve portion to the combination of said pad and said confining sleeve in such manner that the sleeve portion thereof exerts its chief restraining influence on said pad at right angles to the restraining influence exerted by said first mentioned sleeve.

3. The method of packaging a multi-ply, previously compressed and expanded, creped, cellulosic pad of the class described which comprises the steps of providing a rectangularly shaped pad of the said material wherein the creping in the constituent sheets of said pad extends at right angles to the longitudinal axis thereof, recompressing the pad transversely of the direction of said creping to the dimensions desired in the final package, applying a flat, rectangularly shaped confining sleeve to said recompressed pad while said pad is held flat and against expansion or buckling, said confining sleeve having substantially the same longitudinal and perimetrical dimensions as said recompressed pad and the longitudinal axis thereof extending substantially parallel to the lines of creping in said pad, applying an outer wrapping which comprises a flat, rectangularly shaped bag to the combination of said sleeve and pad with the longitudinal axis of said bag extending perpendicular to the lines of creping in said pad, the dimensions of said bag

being only slightly greater than the corresponding dimensions of said pad and sleeve combination, and sealing said outer bag.

4. The method of packaging multi-ply pads of cellulosic sheet material, which pads have been separated from multi-ply webs of said material compressed edgewise in the direction of the length of the web without substantially changing its thickness and width, and which pads have been permitted to expand somewhat during the preparation and delivery thereof for packaging purposes, which consists in recompressing the pad to a predetermined dimension without materially changing the other dimensions of the pad, applying to said pad a wrapper extending therearound in the direction in which the pad is recompressed, said wrapper being of sufficient strength to retain the pad in its recompressed form, and applying to said pad and outside of said wrapper, another wrapper extending around the pad transversely of the direction of said first-mentioned wrapper, said other wrapper serving to impart to the package resistance against buckling whereby the multi-ply pad is maintained in flat, recompressed form.

5. The method of packaging multi-ply pads of cellulosic sheet material, which pads have been separated from multi-ply webs of said material compressed edgewise in the direction of the length of the web without substantially changing its thickness and width, and which pads have been permitted to expand somewhat during the preparation and delivery thereof for packaging purposes, which consists in recompressing the pad to a predetermined dimension without materially changing the other dimensions of the pad, applying to said pad a wrapper extending therearound in the direction in which the pad is recompressed, said wrapper being of sufficient strength to retain the pad in its recompressed form, and applying to said pad and outside of said wrapper, another wrapper extending around the pad transversely of the direction of said first-mentioned wrapper, said other wrapper serving to impart to the package resistance against buckling whereby the multi-ply pad is maintained in flat, recompressed form.

CHARLES A. FOURNESS.
